AUTOMATIC DUMP FOR CARRIER SYSTEMS

Application filed February 3, 1928. Serial No. 251,710.

Our invention relates to an automatic dump, or a device for automatically depositing at a fixed station garment holders which have been transported to said station by a moving cable or rope. The applicants herein are the patentees of a garment conveyor for which Letters Patent of the United States No. 1,645,315 was issued October 11, 1927, and are the inventors of the pick-offs for conveyor systems described in pending application filed May 5, 1924, Serial Number 711,383. The invention described herein is a part of the system for conveying garments from place to place described in said patent and said application. The objects we have accomplished in our automatic dump is a simple, effective and economical device for unloading garments or merchandise suspended by a hook from a moving belt, line, rope or cable which is adapted to transport the same. Other objects will be hereinafter disclosed.

These objects are accomplished by means of the device herein described and illustrated on the accompanying drawing in which Fig. 1 is a side view of a portion of a conveyor system showing the features of our invention. Fig. 2 shows a garment hanger which can be used in connection with the device and is adapted to be conveyed and deposited at the station desired.

As shown in the drawing a beam 8 has depending straps 9 and 10 from which a rigid bar 11 is suspended. Beam 8 can be a portion of the ceiling or roof of the building in which the system is installed or other independent support. The length of the straps 9 and 10 should be such that bar 11 is held in an inclined position. The upper end of bar 11 carries a pulley 12 which is positioned so that the upper portion of its periphery is aligned with, or slightly above the plane of the upper surface of bar 11. At the lower end of bar 11 is a pulley 14 positioned so that the lower portion of the periphery is below the plane of the upper surface of the bar 11. An endless line, cable, belt or rope 15 which is adapted to travel in the direction shown by the arrows 16, is carried on the upper portion of the periphery of pulley 12, and around the lower portion of the periphery of pulley 14. It will be noted

that the rope 15 in its line of travel will pass along a line either on a level with, or slightly above the plane of the highest front of the upper surface of bar 11, and will in its line of travel therefrom drop below the plane of such upper surface. The rope should travel close to the side of bar 11. A garment holder 18, having a hook 19 cooperates with the rope and bar as follows: Hook 19 is engaged with rope at a point in its line of travel before it reaches the bar, and is carried with the rope as the rope moves. When the rope reaches the top plane of the bar, the hook is carried over the top of the bar and deposited and left thereon as the rope then drops below the upper surface of the bar leaving the hook hanging on the bar. The slope of the bar can be sufficient to cause the garment holder to slide to the lower end thereof where it will be stopped by a stop 9^a, this stop being the lower end of strap 9, or if the bar is positioned near horizontally the garment holder can remain in the position where it is deposited by the moving rope until another garment holder is deposited adjacent thereto and moves it forward on the bar. A plurality of said garment holders can thus be deposited on the bar.

A pulley 25 is positioned above pulley 14 for the purpose of guiding the rope beyond bar 11, this being optional in construction. Strap 10 has the lower end bent in the shape of an L or hook so that the main upright portion of the strap can be held a short distance from the side of bar 11, and the support is under the bar, thus allowing the open portion of the hook to pass over that support. It is preferable that the pulleys 12 and 14 be positioned so that the rope will pass along the same side of bar 11 occupied by depending strap 10, and that when the hangers are hooked over the rope the open portion of the hook will be on the side of the bar on which the rope is travelling.

Having described our invention we claim:

1. In combination with a carrier system having an endless moving rope and means for supporting the load to be carried consisting of a plain open hook adapted to loosely engage the rope, an automatic dump comprising a fixed bar positioned so that the entire

top surface of the bar forms an incline sloping in the direction of the travel of the moving rope, the path of travel of said rope being adjacent to, and diagonally across a side face of the bar from the plane of the top surface of said bar.

2. An automatic dump for a carrier system having an endless rope and independent carriage means adapted to be supported on said rope by a plain open hook, consisting of a fixed bar positioned adjacent to the path of travel of the rope so that the entire top surface of the bar slopes downward, the path of travel of the rope being diagonally across the side face of the bar starting at a point aligned with the upper surface of said bar.

WILLIAM L. BIXLER.
L. B. HENRY BIXLER.
